UNITED STATES PATENT OFFICE.

CHARLES PIFER, OF YOUNGSTOWN, OHIO.

DUPLEX TRAIN SAFETY DEVICE.

Application filed March 13, 1926. Serial No. 94,530.

This invention relates broadly to an improved air brake structure for railway equipment, and it has more specific reference to a railway safety appliance such as serves to automatically apply the train brakes in the event the engineer fails to observe caution and danger signals in a block signalling system.

Under ordinary conditions, the handle of 10 the automatic brake valve in the cab is maintained in running position, but when the signals of the block system register "caution" or "danger", the handle is moved to service position, thus reducing the train pipe pressure and automatically applying the brakes.

It has been my experience to note that for various reasons the engineer inadvertently fails to proceed as stated. This results from his failure to see the signal under poor 20 weather conditions, or sometimes from his physical inability to attend to his duties as may be caused from unexpected illness.

Since the failure to apply the brakes at the proper time might result in the serious loss 25 of life and damage, I have conceived and produced a novel structure which will automatically apply the brakes and bring the train to a stop in time to avoid accident.

Briefly, the invention relates to a mechanical system of valve cylinders and piping which is directly associated with the brake valve to momentarily render the latter ineffective by cutting off the supply of main reservoir air and simultaneously relieving 30 the train pipe pressure, whereby to apply the brakes automatically even if the control handle of the automatic brake valve is left in running position.

While the automatic pressure operated 40 system of piping and cylinders is an outstanding feature of the present invention, I wish to mention here that a manually controlled valved device is employed and located within convenient reach of the engineer for the purpose of temporarily throwing the automatic pressure system out of operation.

In addition, mechanical means is provided 50 and carried by the tender to automatically bring said system into play, this being in the form of a novel track controlled device.

Furthermore, an automatic electrical contrivance is employed and associated with the system and also with the track for automatically throwing said system temporarily out of operation in the event that a clear signal

is displayed and an application of the brakes is not desired or required.

Finally, a second electrical contrivance is employed and associated with the automatic brake valve and under the control of the engineer for actuating an electromagnet which is operated to throw said system temporarily out of operation.

The specific details and relative arrangement thereof will become apparent from the following description and drawing.

In the drawings:

Figure 1 is a fragmentary side view of a portion of an engine tender showing a portion of one main rail and an auxiliary rail, together with the mechanical means which is associated therewith for bringing said system into play.

Figure 2 is an end elevation of the structure shown in Figure 1 indicating certain of the parts in dotted lines.

Figure 3 is an enlarged vertical section taken approximately upon the plane of the line 3—3 of Figure 1.

Figure 4 is a horizontal section taken approximately upon the plane of the line 4—4 of Figure 1.

Figure 5 is a detail view of one of the main parts of the so called automatic pressure operated system.

Figure 6 is a horizontal section taken on the plane of the line 6—6 of Figure 5 looking downwardly.

Figure 7 is a top plan view, of diagrammatic form, showing a portion of a conventional block signalling system in order to expedite comprehension of the invention.

Figure 8 is a side view of a part of the railroad track showing the main rail and one of the supplemental rails.

Figure 9 is a section taken through said rails to show the relative arrangement more plainly.

Figure 10 is a diagrammatic outlay of the entire invention, showing the relative relation of parts more in general.

Figure 11 is a diagrammatic view showing a portion of Figure 10 with certain of the parts in an inoperative state.

Figure 12 is a top plan view of a conventional automatic brake valve modified in accordance with my invention and showing the operating handle in service position.

It is believed that a better understanding of the invention may be had by first directing attention to Figure 10 wherein a dia-

grammatic plan of the entire device is indicated in a general way. Referring to this figure it will be seen that the reference character 1 designates an ordinary or conventional automatic brake valve such as is installed in the engine cab within convenient reach of the engineer. The internal construction of this valve is as usual. The stem of the rotary part of the valve however is indicated at 2, is extended above the top of the casing and carries an electrical contact 3 from which an electricity conducting wire 4 extends. Also on top of the casing is an upstanding lug 5 provided with a complementary contact 6 from which a current conducting wire 7 extends. The operating handle 8 is connected to the stem. As before stated, this handle is normally in running position, while the train is moving, but is moved to service position when it is desired to reduce the pressure in the train line and to apply the brake.

Air is supplied from the main reservoir (not shown) through the pipe section 9 to an automatically operated pressure controlled cut out valve 10. The complementary reservoir section 9^a extends from the diametrically opposite side of this valve 10 to the automatic brake valve in the usual way. Leading from the brake valve 1 is a depending pipe section 11 which conducts train line pressure. This may sometimes be referred to as the train pipe. That portion 12 leads to various cars of the train, while the portion 13 extends to an auxiliary reservoir 14 for a purpose to be hereinafter described. Connected with the main reservoir pipe section 9 is a right angular branch pipe 15 which is in turn connected to a control valve 16 for said supplemental automatic system. At this time I would direct attention to the conventional reducing valve 17 which is connected with the reservoir pipe section 9 by way of the short pipe 18, and is connected with the cut out valve 10 by a branch pipe 19, and with the control valve 16 by a branch pipe 20 thus serving to introduce pressure into the cylinders of these respective valves 10 and 16 for maintaining them normally open as shown in Figure 10. Attention is now called to an automatically operable pressure exhausting and relief valve 21. It will be noted that a pipe 22 affords communication between the control valve 16 and the relief valve 21. This pipe 22 carries main reservoir pressure which is received from the aforesaid angular branch 15 when the valve 16 is open. Beneath this pipe 22 at the right hand end is a short pipe section 23 which extends from the aforesaid train line pressure pipe 13 to the valve 16. A return pipe 23^a serves to conduct this train pressure air when the valve 16 is open to the lower portion of the valve 21. Leading

from the top portion of the relief valve 21 is a further pipe 24 which has an upwardly directed portion which connects with the aforesaid cut off valve 10.

The parts so far described constitute the major portion of the so called automatic pressure operated system which is directly associated with the automatic brake valve 1. If desired, three indicating gages 25, 26, and 27 may be employed. The gage 25 is connected through a pipe 28 with the train line pressure pipe section 23^a. The gage 26 is connected with the main reservoir pressure conducting pipe section 22, while the remaining gage 27 is connected through a pipe 30 with the exhaust pressure conducting branch pipe 24.

As before stated, the handle 8 of the automatic brake valve 1 is normally maintained in running position when the train is traveling under normal conditions. If, however, the engineer wishes to bring the train to a stop, he moves the handle from running

position to service position and this reduces the pressure in the train line pipe to automatically apply the brakes. It is obvious that this operation is not interfered with by the presence of the supplementary system,

for air comes from the main reservoir (not shown) through the pipe section 9, then through the normally open cut off valve 10, and branch section 9^a into the brake valve 1. It then flows off through the train line pressure conducting pipes 11, 12, and 13, and carries on its usual work. Assuming how-

ever that the signals of the conventional block signalling systems are to be observed and that the train is to be brought to a stop when a danger or a caution signal is shown, it is well known that as such signals are frequently inadvertently unobserved and for other reasons stated, the handle 8 being left in running position might result in considerable damage. At this point in the description attention is directed to Figure 7 where-

in a diagrammatic view shows three sections of a conventional block signalling system. More specifically, this view simply shows the main rail 31 of the left hand section, the main rail 32 of the central section, and the main rail 33 of the right hand section.

In accordance with my idea, supplemental raised rails 34 are placed alongside of the main rails in each instance, the main rails being insulated from each other in the usual way, and current supply wires 35 and 36 being connected to the supplemental rails in each instance. As is customary, the wires lead from the current supply batteries of

the conventional block signalling system and as is known by persons skilled in the art. When a clear or safety signal is given in the signalling system, current will be conducted through the wires 35 and 36 to the supplemental rails 34. The purpose of this

85

130

arrangement will be made clear later in the description. At this time it is sufficient to state that the main purpose of using the supplemental rail is to bring the pressure supply system temporarily into play so that the brakes will be automatically applied every time the supplemental rails are encountered. In Figures 8 and 9 it is apparent that the main rails are of customary design and the supplemental rail 34 is in, each instance, of special form and comprises a central flat portion and downwardly directed end portion, the same being supported from brackets 37 of I-shaped cross section. These brackets are positioned alongside of the rail 33 as shown in Figure 9 and are located at proper points to provide for the desired clearance for brake beams or other hanging contrivances carried by trains. The elevation of the supplemental rails will be governed according to various circumstances.

As before intimated, mechanical means is employed for operating the supplemental brake applying systems and by directing attention to Figure 1 it will be seen that this means comprises a structure suspended from the tender 38. This structure comprises a pair of appropriately shaped hangers 39 disposed in spaced parallelism. The intermediate portion of these hangers, which are in the form of metal strips are flattened somewhat as indicated at 40. Then vertical braces 41 are connected thereto to insure rigidity of construction. Passing through the portions 40 of the hangers and through the top connecting bar 42 are four bolts 43 upon which a vertically liftable plate 44 is slidably mounted. Coiled springs 45 surround the bolts and bear upon the plate and serve to maintain the latter normally in a predetermined position. Above the movable plate 44 is a stationary plate 46 which is appropriately bolted in place and is maintained in a predetermined position by the spacing sleeve 47. Carried by the central portion of the movable plate 44 and insulated therefrom is a channel shaped member 48 carrying a journal pin upon which a roller 49 is mounted for rotation. The head of a plunger 50 rests upon the central portion of the plate 44 and extends upwardly through the top bar 42. Obviously then, as the roller 49 rides up on the supplemental rails 34, it raises the plates 44 upward against the action of the coil springs 45. In so doing, it also raises the plunger 50 upwardly.

At this time I would state that while I have shown the relief cylinder 21 more or less in a diagrammatic way in Figure 10, it is actually of a special design such as indicated in Figure 1 and in detail in Figures 5 and 6.

Attention is first directed to Figure 1

wherein it will be seen that an appropriate support 51 is provided as a mounting for this valve, the valve being disposed in the vertical position. However, in practice it may be located in any convenient way on the lower portion of the tender so that it will be operated by the plunger 50. In Figure 5, it is obvious that the valve 21 comprises a suitably constructed cylinder 52 mounted upon a stationary support 51. Slidable in this cylinder is a piston comprising vertically spaced disks 53 and a stem 54 connected at its upper end to a cross piece 55 which is in turn connected to connecting rods 56 which extend slidably through the support 51. Then there is another cross piece 57 at the lower ends of the rods and this carries a depending part 58 with which the upper end of the aforesaid plunger 50 is adapted to engage. A spring 59 cooperates with the cross piece 57 to maintain the piston in the position shown in Figure 5. If desired, the wall of the cylinder may be enlarged and channelled as indicated at 60. This will facilitate the entrance and circulation of air.

The operation of the device as far as it has been thus described, is as follows—The air comes from the reservoir in the usual way and passes through the pipe sections 9 and valve 10, and pipe section 9^a to the automatic brake valve. From the automatic brake valve it passes through the train pressure pipes 11, 12, 13, 23, and then into the cylinder of the valve 16. This valve simply comprises a cylinder and a floating piston of the construction shown. This is also true of the valve 10. When the piston is in the position shown in Figure 10, the train line pressure circulates through the cylinder of the valve 16 and returns through the return pipe 23^a and into the valve cylinder 21.

At the same time the air pressure passes upwardly through the branch 18 from the main reservoir into the reducing valve 17 and then through the branches 19 and 20 into the top chambers of the valves 10 and 16 respectively, thus maintaining the pistons in these two valves open. In addition, reservoir pressure air passes through the right angular branch 15 across the cylinder 16 into the pipe section 22 and into the valve 21. It will be noted however, that at this time the piston in the valve 21 is closed. Assuming however, that the train enters a block signalling system, it will be seen that each section of the system is encountered, the supplemental raised rails will operate the roller or shoe in a way to lift the plunger 46. In so doing, the reciprocating valve piston in the relief valve 21 will be raised to the position shown in Figure 11. Obviously then, the train pressure air coming from the branch 23 will flow into the lower chamber of this valve and will escape through an

exhaust pipe 61. Simultaneously air passing through the main reservoir pressure conducting pipe section 22 will flow into the valve cylinder 52 and will pass on through the exhaust pipe section 24. In so doing it will lift the valve piston in the cut-off valve 10, thus cutting off the supply of main reservoir air to the automatic brake valve 1. Obviously, then as the train pipe pressure is 5 exhausting through the valve 21 and the exhaust pipe 61 and as the source of supply of air to the automatic brake valve has been cut off, there will be a reduction by this exhausting into the atmosphere which will serve to 10 automatically apply the brakes of the train regardless of the position of the brake handle 8. It follows that if the engineer entered the block signalling system and a danger or a caution signal was displayed 15 20 and he did not see it, and the handle was in running position, the supplemental system or brake applying device will come automatically into play and apply the brakes. Of course, as soon as the shoe resumes its 25 normal position under the action of the spring means provided, the parts of the device will return to their normal position when the train line pressure is reduced to atmospheric pressure and the device will not 30 operate until it encounters the next supplemental rail.

It is obvious that the device is ideal in case the engineer did not see the signal, and did not bring the train to a stop, or if for any 35 reason that he is physically unable to attend to his duties at this time. On the other hand it may not be desirable to permit the automatic device to operate under all conditions, particularly if a clear signal is displayed in the block and the engineer is on 40 the job. It therefore follows that it is desirable to provide a means under the control of the engineer for throwing the device out of play. This is done in the present case by 45 the provision of a hand controlled valve 62 which is located alongside of the automatic brake valve 1. This valve 62 includes an operating handle 63. In addition, a pipe 64 is connected thereto below the valved diaphragm, and this pipe it will be seen is connected with the main reservoir supply pipe section 9. Then too, another pipe 65 is connected with the valve casing above this diaphragm, and this leads downwardly to and is 50 connected with the bottom of the aforesaid valve 16 by way of the short connection 66. It follows that when the valve handle 63 is 55 depressed, air will flow directly from the main reservoir through the pipe 64 and upwardly through the open diaphragm in the valve 62 and then through the pipe 65 to the control valve 16. The reservoir air pressure underneath the floating piston in this valve 60 65 will lift the piston up to a position to cut off communication between the pipes 15 and

22 in one instance, and 23 and 23^a in the other instance. Thus, even if the valve 21 is operated when the next supplemental rail is encountered the device will not be effective.

Referring now to Figures 10 and 11, it 70 will be seen that the reference character 67 designates generally an electromagnetic valve which includes a core 68 and an especially constructed casing for accommodating a gravity closed valve 69. This valve operates in a suitable chamber and serves to close a passage extending down into a bottom chamber 70. It will be noted that a relief port 71 connects with this passage. In addition, there is a pipe 72 which connects with the upper chamber and with the branch pipe 15, thus conducting the main reservoir air from the pipe section 9 through the pipe 15, pipe 72 and into the valved chamber. When the valve 69 is open, the air passes 75 down into the lower chamber 70 and through a pipe section 73, portion 66 and into the casing of the valve 16. This constitutes an electrical contrivance which in effect does the same thing that the mechanical means 80 85 90 95 100 105 110 115 120 125 130 135 140 145 150 155 160 165 170 175 180 185 190 195 200 thus throwing the device out of operation.

From the foregoing description it will be seen that an automatic brake applying device is directly associated with the automatic brake valve 1, this device including a trio of valved cylinders, and piping, the piping being appropriately arranged so that under normal conditions air comes from the main reservoir to the automatic brake valve

10 and flows through the train pipe in the usual way unaffected by the presence of this invention. However, when a block signalling system is encountered and the supplemental rails are also encountered, the

15 shoes on opposite sides of the tender serve to operate the plungers which in turn operate the relief valves 21 to bring the device into play and to allow a reduction in the train pressure line and to simultaneously cut off the main reservoir supply to the automatic brake valve, thus applying the brakes regardless of the position of the handle. It follows that if the handle is left in running

20 position, this is immaterial because this device operates automatically to apply the brakes in case of danger. If, however, the engineer desires to throw the device out of operation, this may be done with the mechanical means 62, or with the electrical

25 means comprising the electric circuit controlled by the operation of the handle 8 when in service position, or further by the automatic electrical means which is operated through the supplemental rails. The only

30 time that the last named electrical device operates, is only when a clear signal given for this is the only time that the supplemental rails 34 will be energized from the signal batteries.

35 It is believed that the features and advantages of the invention will become apparent from the foregoing description and drawing. Persons skilled in the art will no doubt be able to obtain a clear understanding of the invention, for this reason a more lengthy description is thought unnecessary.

40 Minor changes coming within the field of invention claimed may be resorted to if desired.

45 Having thus described the invention, what I claim as new and desire to secure by Letters Patent is:—

1. In an air brake structure of the class described, an automatic brake valve, and an automatic device controlled by reservoir air pressure and associated with said valve for simultaneously cutting off the main reservoir supply of air to the brake valve and permitting a reduction in the train line pressure in order to automatically apply the brakes even when the operating handle of the valve is in running position, and electrical means associated with the automatic brake valve handle and said device for

45 throwing said device temporarily out of operation when the brake valve handle is moved to service position.

2. In an air brake structure of the class described, in combination, an automatic brake valve, an automatic reservoir pressure controlled device associated with said brake valve for simultaneously cutting off the main reservoir supply of air to said brake valve and permitting a reduction in the train line pressure in order to automatically apply the train brakes even when the operating handle of said valve is in running position, a manually operated hand controlled device associated with said pressure operated device for throwing the latter out of operation at the discretion of the engineer and electrical means independent of said hand operated device, associated with the automatic brake valve handle and said pressure controlled device for throwing said device 80 temporarily out of operation when the brake valve handle is moved to service position.

3. In an air brake structure of the class described in combination, an automatic brake valve, a cut off valve, a main reservoir pipe section connected with said cut off valve, a second main reservoir pipe section connected with said cut off valve and with said automatic brake valve, a relief and exhaust valve connected with said cut off valve, a train pressure pipe connected with said automatic brake valve, a control valve with which said train pressure pipe is connected, a return pressure pipe connected with said control valve and also with said relief valve, 90 and a main reservoir air supply pipe connected with said control valve and with said relief valve, and a conducting pipe affording communication between said cut off valve 95 and relief valve.

4. In an air brake structure of the class described in combination, an automatic brake valve, a cut off valve, a main reservoir pipe section connected with said cut off valve, a second main reservoir pipe section connected with said cut off valve and with said automatic brake valve, a relief cylinder in communication with said cut off valve, a train pressure pipe connected with said automatic 110 brake valve, a control valve with which said train pressure pipe is also connected, a return pressure pipe connected with said control valve and also with said relief valve, a main reservoir air supply pipe connected with said control valve, a conducting pipe 115 affording communication between said cut off cylinder and relief valve, an electromagnet valve associated with said control valve, piping connecting said magnetic valve with said control valve, and electrical means for 120 energizing the magnet in said valve.

In testimony whereof I affix my signature.

CHARLES PIFER.
